UNITED STATES PATENT OFFICE.

ARTHUR LOWY, OF NEWARK, NEW JERSEY, ASSIGNOR TO NEW YORK ENGINEERING COMPANY, A CORPORATION OF NEW YORK.

BOILER-TUBE CLEANER.

Application filed March 5, 1921. Serial No. 449,803.

To all whom it may concern:

Be it known that I, ARTHUR Lowy, a citizen of the United States, and resident of Newark, in the county of Essex and State of New Jersey, have invented certain new and useful Improvements in Boiler-Tube Cleaners, of which the following is a specification.

This invention relates to reciprocatory tools such as boiler tube cleaners, and more particularly to that type of cleaner in which the boiler scale is directly cut or chipped away by the action of a sharp edged tool, rather than by repeated hammer blows. In this invention the cutting tool is given a rapid reciprocating movement, and is simultaneously given a rotary movement which greatly increases its cutting action. The actuating mechanism is driven by fluid pressure, such as steam or compressed air, and in order to secure simplicity and compactness is characterized by having a stationary piston and movable cylinder carrying the tool with the ports automatically controlled by the cylinders. The exhaust is utilized to rotate the cylinder by reaction without requiring additional parts.

In carrying out this invention I have devised an apparatus which is compact in structure, simple of design, easy to operate and economical to manufacture, the same being described in the following specification, and illustrated in the accompanying drawings, of which

Figure 1 is a view in longitudinal section, Figure 2 is a transverse section on the line II—II of Figure 1, and

Figure 3 is a transverse section on the line III—III of Figure 1.

1 denotes a cylinder comprising cylinder head 2 and cylinder wall 3, the former being threaded into the latter and held by a pin 4 extending diametrically through the threaded portion to prevent relative rotation. Cylinder 1 reciprocates over piston 5 which is rigidly secured to, or preferably integral with, piston rod 6, and being heavy has the advantage of mass directly carrying the tool. The end of cylinder wall 3 opposite the cylinder head 2 has a contracted opening 7 adapted to fit over piston rod 6 and to provide a long bearing therefor which is intended to serve also as a valve as will be hereinafter explained. Packing 8 is pro-

vided to prevent escape of fluid pressure. 55 Piston rod 6 is provided at its free end with annular notches 9 to engage the end of a flexible tubing (not shown) which conveys the motive fluid to the cylinder. Piston rod 6 is provided with a passageway 10 and in piston rod 6 adjacent piston 5 is a port 11 which communicates with passageway 10 and provides access for the motive fluid into the cylinder. Communicating with the space between piston 5 and cylinder head 2 is a passageway 12 and spaced from piston 5 in piston rod 6 is a port 13, which together with passageway 12 provides communication between the spaces within the cylinder upon either side of the piston 5. Port 13 being 65 spaced from piston 5 will be alternately closed and opened as the end 7 of cylinder wall 3 reciprocates thereon. In cylinder wall 3 and communicating with the cylinder space between cylinder head 2 and piston 5 when cylinder 1 is in advanced position, are exhaust ports 14, which are opened and closed by piston 5 as cylinder 1 reciprocates thereon, permitting the spent motive fluid to exhaust into the atmosphere when cylinder 1 is at or near the end of its stroke. Exhaust ports 14 are preferably multiple, comprising a plurality of passageways distributed about the periphery of the cylinder, but whether single or multiple, are disposed non-radially 70 so that the reaction of the escaping fluid will cause rotation of cylinder 1. 75

The motive fluid which is admitted through port 13 will expand after port 13 is closed by the outward travel of the cylinder. This will cause the pressure to fall, and in order to maintain sufficient pressure to force the cylinder to the end of its stroke, space must be provided to receive a sufficient quantity of the motive fluid. This is accomplished by enlarging passageway 12 and hollowing piston 5 as at 15 to form a reservoir, cylinder head 2 being similarly hollowed as at 16. By utilizing the space thus available the cylinder may be made very short. 80 85 90

The inner face of cylinder head 2 is finished off as at 17 to provide an abutment for piston 5 and thus to limit the inward travel of the cylinder while the inner space 24 of contracted opening or bearing 7 is similarly finished off and serves as a stop for the outward travel of the cylinder as the piston 5 contacts therewith. In practice, 100 105

these surfaces do not necessarily abut, as sufficient motive fluid is trapped at each end to act as a cushion.

Scale chipping tool 18 is circular in form and is about $\frac{1}{4}$ inch less in diameter than the tube in which it is to be used, and is provided with a series of annular cutting edges 19 extending in the direction in which the tool is to be advanced, and which are 10 adapted for chipping and cutting the scale and for scraping the inside of the boiler tube. Scale cutting tool 18 is provided with lug 20 which is carried loosely in a recess 21 of lug 22 upon the end of cylinder head 15 2. A pin 23, detachably secured in lug 22 and loosely fitting through lug 20, holds scale cutting tool 18, the loose fit permitting a slight universal movement of scale cutting tool 18. By making the cutting 20 tool 18 detachable, the same cylinder and piston mechanism may be employed in various size boiler tubes, the size of cutter being selected in accordance with the diameter of the tube. Also, various kinds of 25 tools may be used.

In operation the motive fluid, which may be steam or compressed air, enters passageway 10 and thence through port 11 flows into the cylinder space surrounding the piston rod. Port 13 is so spaced with relation to contracted end 7 as to be open when cylinder 1 is in retracted position. The fluid under pressure surrounding piston rod 6 now enters port 13 and exerts its pressure 30 upon cylinder head 2 forcing the cylinder head outward to its advance position. The area of cylinder head 2 being greater than the area of inner surface 24, equal pressures 35 on both sides of the piston will cause outward movement of cylinder 1. After cylinder 1 has advanced over a portion of its stroke, port 13 is covered by contracted end 7 which serves as a valve, and the supply 40 of motive fluid to the cylinder head is cut off; but the fluid within passageway 12 and the hollow space between cylinder head 2 and piston 5 will expand and continue to force cylinder head 2 outwardly. As cylinder head 2 approaches the outward limit 45 of its travel port 14 will now be uncovered permitting the fluid within passageway 12 and the hollow space between piston and cylinder head to exhaust into the atmosphere, port 14 being disposed non-radially causing 50 the cylinder to rotate by the reaction of the exhaust. When all the fluid is thus exhausted the cylinder 1 will be retracted by the pressure of the fluid within the cylinder surrounding the piston rod 5 acting upon 55 the inner surface 24 of contracted end 7 until port 13 is again uncovered permitting the access of fluid to passageway 12 whereupon the aforesaid cycle will be repeated. It will be seen that supply pressure is always 60 on surface 24, but is overcome on the

forward stroke by the supply pressure on the greater area of head 2, while the return stroke is by supply pressure on surface 24 after the pressure has exhausted 70 low enough, the supply pressure used on the return stroke assisting in charging the cylinder for the forward stroke. Hence the interior volume must be sufficient to drive the cylinder the full stroke after the cut-off at port 13. 75

Cutting tool 18 is thus reciprocated and rotated, and its various cutting edges will engage the scale according to the thickness of the same, the inner edges first attacking the thicker portion of the scale, and the outer edge removing the last traces of scale by scraping the inside of the tube. While scale cutting tool 18 is of less diameter than the boiler tube, it will be drawn, by virtue 80 of its universal connection with the cylinder, in whatever direction the scale is most resistant, and as the scale is reduced, will contact and scrape the interior of the tube itself. The tool being nearly the diameter 85 of the tube, vibration will be sufficient to cause it to engage the scale on all sides, even where the latter is very thin. 90

The tubing which supplies motive fluid to the device and upon which piston rod 6 is carried, should be sufficiently flexible to permit in conjunction with the overall shortness of the device, insertion in curved tubes, yet stiff enough to advance the cutting edges up to the working point. In case the cylinder stops with both ports closed, the mechanism can always be started by either pushing or pulling upon the tubing. 95

The device provides a minimum of parts, with only one moving part and one packing, is very short, can thus work in curved as well as straight tubes, and can be applied to fluid operated tools generally without material change. 10

What I claim is:

1. A fluid pressure percussion tool comprising a stationary ported member, having connection to a source of fluid pressure supply, a reciprocating member adapted to rotate and having an exhaust port for the escape of the motive fluid disposed non-radially to cause rotation, and tool attaching means carried by said reciprocating member. 11

2. A fluid pressure percussion tool comprising a stationary piston, a cylinder reciprocating thereon, tool attaching means carried by said cylinder, means for maintaining a continuous supply of fluid under pressure upon one side of said piston, means for intermittently supplying fluid through said piston to advance the cylinder, means for exhausting the fluid supplied through said piston near the end of the advance stroke, exhaust actuated means for rotating the cyl- 12 13

inder, and means for returning the cylinder to its initial position.

3. A fluid pressure percussion tool comprising a stationary piston, a cylinder adapted to reciprocate thereon having at one end a closed cylinder head and at the opposite end a contracted opening, a piston rod having a passage therein secured to said piston and adapted to fit within said contracted opening, means for connecting said passage to a source of fluid pressure, a port in said piston rod adjacent said piston, an admission passageway in said piston rod and piston completely within the cylinder, controlled by movement thereof, and leading to the space between said cylinder head and said piston, a port in said piston rod spaced from said piston and communicating with said last passageway, said port being alternately closed and opened by said contracted end of the cylinder as the same reciprocates thereover, and an exhaust port in the cylinder wall communicating with the space between the cylinder head and the piston, said exhaust port being alternately closed and opened by said piston as the cylinder reciprocates thereon, and tool attaching means carried by said cylinder.

4. A fluid pressure percussion tool comprising a piston, a cylinder adapted to reciprocate thereon having at one end a closed cylinder head and at the opposite end a contracted opening, a piston rod secured to said piston and adapted to fit within said contracted opening, said piston rod having a passage therein, means for connecting said passage to a source of fluid pressure, a port in said piston rod adjacent said piston communicating with said passage, a passageway in said piston rod and piston leading to the space between said cylinder head and said piston, a port in said piston rod spaced from said piston and communicating with said last passageway, said port being alternately

closed and opened by said contracted end of the cylinder as the same reciprocates thereover, a non-radial exhaust port in the cylinder wall communicating with the space between the cylinder head and the piston, said exhaust port being alternately closed and opened by said piston as the cylinder reciprocates thereon, and causing rotation of the cylinder as the fluid escapes, and tool attaching means carried by said cylinder.

5. In combination, a stationary piston and piston rod, a movable cylinder slidably thereon, said piston rod being provided with a plurality of passageways therein for a motive fluid, a rotary percussion tool secured adjacent an end wall of the cylinder and adapted during its rotation to have a slight universal movement, the tool carrying end of said cylinder and the adjacent side of said piston being recessed to form an expansion chamber for said motive fluid, said cylinder being of smaller diameter than the tool and provided with means for being rotated by the motive fluid.

6. The combination with a stationary piston rod provided on one end with means for attaching a fluid supply hose, of a plurality of fluid supply passageways in said piston rod, a piston on the other end of said rod from the supply hose, a reciprocal cylinder mounted on the piston rod and piston, packing between said cylinder and piston rod on the end portion of said cylinder adjacent the supply hose, a rotary percussion tool of larger diameter than the cylinder secured close to the other end thereof from said packing, means to intermittently supply a motive fluid to the cylinder and means intermittently effective to rotate the cylinder.

Signed at New York city in the county of New York and State of New York this 3rd day of March A. D. 1921.

ARTHUR LOWY.
